UNITED STATES PATENT OFFICE.

ALEXANDER MUIRHEAD, OF LONDON, ENGLAND.

DUPLEX AND QUADRUPLEX TELEGRAPHY.

SPECIFICATION forming part of Letters Patent No. 280,753, dated July 3, 1883.

Application filed November 27, 1882. (No model.)

To all whom it may concern:

Be it known that I, ALEXANDER MUIRHEAD, a subject of the Queen of Great Britain, residing in London, England, have invented certain new and useful Improvements in Duplex and Quadruplex Telegraphy, of which the following is a specification.

My invention relates to certain improvements in the construction and arrangement of apparatus and circuits for multiple-telegraph systems.

Serious hindrances to the successful operation of multiple telegraphs have heretofore been encountered, which have been due to the effect upon receiving-instruments of electrostatic charges and discharges passing to and from the lines. Various means have been devised and methods adopted in order to counteract these effects and to eliminate or reduce their causes. These methods, for the most part, depend upon the employment of an artificial or equating line having a resistance approximately equal to that of the main or actual line, and which is arranged to be charged and discharged simultaneously therewith, the design being to oppose the static effects of the artificial to those of the main line, and thus cause them to neutralize the effect of each other upon the receiving-instruments. In practice, however, it has been found that although the resistances of the main and artificial lines may be equal, yet, owing to the fact that while the one consists of a long line of high degree of conductivity, the rate with which permanent currents from a given electro-motive force establish themselves in the two will differ materially. From this difference in the rates of charging and discharging it results that when batteries of equal electro-motive force are simultaneously connected with the main and artificial lines the electrical potential at the terminal of the main line, which has thus been attached to the battery, falls below the normal potential of the latter with a rapidity dependent upon the rapidity with which the current flows into the uncharged conductor beyond. In like manner the fall of potential of the connected terminal of the artificial line depends upon the rapidity of the outflow of the current through that conductor. Hence the potential of the transmitting terminals of

the respective lines will continue to be unequal until both lines become fully charged, or until the rapidity of the outflow upon the two lines has been rendered equal. In certain systems 55 of multiple telegraphy this difference in potential reacts upon the receiving-instruments at the transmitting-station, rendering the operation of simultaneously transmitting and receiving over a single conductor exceedingly difficult.

The object of my invention is to so organize and arrange the circuits in a multiple-telegraph system, in which currents are simultaneously transmitted from batteries or battery-sections of equal electro-motive force through a main and an artificial line, that the potentials at the respective transmitting terminals shall be rendered approximately equal at all times, and to so arrange the apparatus 70 at the respective terminals of the main line that currents possessing the necessary characteristics for the various classes of multiple telegraphy may be readily transmitted and received.

To this end my invention consists in combining with a main and artificial line a series of batteries or battery-sections and means for simultaneously placing equal portions thereof in electrical connection with the main and artificial lines, respectively, and means for maintaining the potential of the transmitting terminals of the two lines approximately equal. These may consist either of a shunt-circuit of considerable resistance around the portion of the battery connected with the artificial line, within which shunt is included an adjustable inductor consisting of a coil of insulated wire surrounding a soft-iron bar, by means of which the rapidity with which an electric current is 90 allowed to flow from the connected terminal of the battery may be accurately adjusted; or of a shunt around the portion of the battery connected with the main line, in which is included a condenser the charge of which will be 95 liberated simultaneously with the transmission of each impulse or signal, and will thus serve to maintain the potential at the terminal of the battery transmitting the impulse upon the main line at the same point as that 100 of the battery momentarily connected with the artificial line.

The invention also comprises certain details in the construction and arrangement of the apparatus, hereinafter fully set forth.

In the accompanying drawings, Figure 1 is a diagram illustrating my invention as applied to quadruplex telegraphy, and Fig. 2 illustrates a convenient method of constructing the adjustable inductor shown in Fig. 1. Fig. 3 is a diagram exhibiting certain modifications in the application of the invention.

Referring to the diagram, L represents the main line or conductor of a telegraphic system, and l an artificial line in which is included an artificial resistance, X, approximately equal to that of the main line.

K and K' represent two independent keys or equivalent devices for transmitting through the main line L and the artificial line l currents of different strengths derived from a series of batteries, O' O² O³ and o' o² o³. The key K consists of a lever, k, pivoted at n, and extending between two insulated contact-springs, a and b. Two contact-points, c and d, are carried at the extremity of the lever k, for placing the same in electrical connection with one or the other of the springs a and b, according as the key is raised or depressed.

Between the springs a and b is placed an insulated resting-contact stop, e, with which the springs a b make contact when not pressed away by the key-lever k.

The transmitting device K' is precisely similar in mechanical construction to the key K, consisting of a lever, k', contact-springs a' b', contact-points c' d', and resting-contact e'.

The batteries O' and o' consist of an equal number of cells, or possess equal electro-motive forces, and they respectively have one pole of opposite denominations connected with the main and artificial lines L and l. Thus the battery O' has its positive pole connected by a wire, 1, with the main line L, and the battery o' its negative pole connected by a wire, 2, with the artificial line l. The remaining poles of the two batteries are respectively connected by the wires 3 and 4 with the key-lever k and resting-contact e.

The batteries O² and o², which are each assumed to have an electro-motive force two-thirds as great as that of the batteries O' and o', respectively, are connected as follows: The battery O² has its negative pole connected by a wire, 5, with the contact-spring b of the key K, and its negative pole by a wire, 7, with the key-lever k' of the key K'. The battery o² has its positive pole connected by a wire, 6, with the remaining contact-spring a of the key K, and its negative pole by a wire, 8, with the resting-contact e' of the key K'.

The batteries O³ and o³ are each assumed to have one-half the electro-motive force of the batteries O² or o², or one-third that of the batteries O' or o'. The battery O³ has its negative pole connected by a wire, 9, with the contact-spring b' of the key K' and its positive pole with the earth at G through wires 11 and

13. The positive pole of the battery o³ is connected by a wire, 10, with the remaining contact-spring a' of the key K' and the negative pole by wires 12 and 13 with the earth at G. 70

It is evident that when the keys K and K' are in their normal position, as shown in the diagram, the negative pole of battery O' will be connected, through wire 3, key-lever k, contact-point d, contact-spring b, and wire 5, with the negative pole of the battery O². The positive pole of this battery O² is normally connected, through wire 7, key-lever k', contact-point d', contact-spring b', and wire 9, with the negative pole of the battery O'. The positive pole of the battery O³ is connected, as already described, with the earth at G. The two batteries O² and O³, having a combined electro-motive force equal to that of the battery O' and opposed thereto, transmit no current to the line L. In like manner the batteries o² and o³ are normally opposed to the battery o', the latter having its positive pole connected, through wire 4, resting-contact e, and spring a, with the positive pole of the battery o², the negative pole of which is connected, through wire 8, contact e', spring a', and wire 10, with the positive pole of the battery o'. No current is therefore normally transmitted upon the artificial line l. 95

Assuming the batteries O' and o' each to have an electro-motive force of one hundred and fifty volts, the batteries O² and o² of one hundred volts, and the batteries O³ and o³ of fifty volts, by depressing the keys K and K' separately and in combination, currents of the following resultant strengths will be sent to both the main and artificial lines. When the key K alone is depressed, the connections of the batteries O², o², O³, and o³ will be reversed with reference to the batteries O' and o' and the main and artificial lines. The negative pole of the batteries O² and O³ will be united to the positive pole of the battery o' through the wire 5, spring b, stop e, and wire 4, while the positive poles of the batteries o² and o³ will be united to the negative pole of the battery O' through wire 6, lever a, lever k, and wire 3. Each system of connected batteries being now included in circuit in the same direction, a positive current from an electro-motive force of three hundred volts will be transmitted to the main line L and an equal negative current to the artificial line l. When the key K' alone is depressed, the batteries O² and o³ only are reversed with reference to the remaining batteries and the main and artificial lines. The negative pole of the battery O³ is connected, through wire 9, spring b', resting-contact e', and wire 8, with the negative pole of the battery o². The positive pole of the battery o² is at the same time connected, through the wire 10, spring a', lever k', and wire 7, with the positive pole of the battery O². Positive and negative currents corresponding to an electro-motive force of one hundred volts will therefore be transmitted upon the main and artificial lines, respectively, when the key 115 120 125 130

K' alone is depressed. When both keys K and K' are simultaneously depressed, the negative and positive poles of the batteries O' and o', respectively, will be connected with the like poles of the batteries O² and o², respectively, in the same manner as when the key K alone is depressed, except that in the present instance the polarity is reversed. The resultant currents sent to the main and artificial lines will 10 be positive and negative currents, respectively, due to an electro-motive force of two hundred volts. The three classes of currents thus produced may be employed at the receiving-station for actuating two receiving-instruments, 15 one or the other, or both, responding, accordingly as one or the other or both keys are depressed. The apparatus which I prefer to employ for this purpose is illustrated in connection with the transmitting devices shown in 20 Fig. 1, the apparatus at the distant station being precisely similar thereto.

R and R' represent the two receiving-instruments, designed, respectively, to respond to currents from electro-motive forces of three 25 hundred and one hundred volts, while both respond to currents from an electro-motive force of two hundred volts. In order to effect this result, the receiving-instrument R consists of an ordinary electro-magnet, M, having its 30 respective coils m n included in the circuits of the conductors 1 and 2, leading from the battery-sections O' and o' to the lines L and l. The coils m and n are so connected that magnetism of like polarity will tend to be induced 35 in the poles of each core when the circuit-connections of the local batteries are completed, and its armature r will therefore not be affected by the operation of the transmitting-keys at the home station. A tension-spring, 40 t, normally exerts sufficient force upon the armature r to prevent it from responding to currents proceeding from the distant station when corresponding to an electro-motive force not exceeding one hundred volts. The tension is, however, insufficient to resist the action 45 of a like current corresponding to an electro-motive force of two hundred or more volts. The receiving-instrument R therefore responds to currents transmitted from the distant station by closing the key K, either alone or simultaneously with the closing of the key K' at the same station.

It is evident that both coils of the electro-magnet M might be included in the conductor 55 13, leading from the junction of the conductors 11 and 12 to the earth; but for the purpose of reducing the resistance of the circuit I prefer to include it in the circuits of both the conductors 1 and 2, as described. 60 It is evident, moreover, that, as the receiving-instrument R is designed to respond only to currents of considerable intensity, the magnetism induced by the incoming current while traversing one coil, m, only of the magnet M 65 will be sufficient to serve all the requirements. The receiving-instrument R' is preferably in-

cluded in the circuit of the conductor 13, leading from the junction of the conductors 11 and 12 to the earth. It consists of a single electro-magnet, M', having two oppositely-polarized armatures, r' and r², corresponding, respectively, to its two cores. Two contact-stops, S' and S², and two banking-screws, S³ and S⁴, are respectively provided, against which the armatures r' and r² are thrown when under the 70 magnetic influence of the various changes in the strength of currents traversing the line. Suitable tension-springs, t' and t², are provided for normally maintaining the armatures r' and r² in contact, respectively, with the banking-screw S³ and contact-stop S⁴. The armatures r' and r² are normally in electrical connection with each other through the conductor n, and the contact-stops S' and S² are also in electrical connection with each other by means of a 80 conductor, 14, in the circuit of which is included a local battery, p, and sounder p'. It will now be evident that the sounder p' will be actuated whenever the circuit of the battery p is completed therethrough by the simultaneous contact of the armatures r' and r² with their respective contact-stops S' and S².

For the purpose of rendering the instrument R' capable of responding to currents proceeding from an electro-motive force of 95 one hundred and two hundred volts, but not of three hundred volts, the tension of the retractile spring t' is so adjusted that the polarized armature r', while normally held against the banking-screw S³, will respond to 100 an incoming current from an electro-motive force of one hundred volts, and will thereby be thrown against the contact-stop S'. The same current, however, will be insufficient to actuate the armature r²; hence the circuit of 105 the local battery p will be closed and the sounder p' actuated. A current corresponding to an electro-motive force of two hundred volts will also be sufficient to actuate the polarized armature r' in the same manner as 110 just described, but will be insufficient to actuate the armature r². The sounder p' will therefore respond to incoming currents, whether from an electro-motive force of one hundred or of two hundred volts. An incoming 115 current from an electro-motive force of three hundred volts will, however, in addition to actuating the armature r', be sufficient to actuate the armature r² against the force of its retractile spring and carry the armature r² 120 away from its contact-stop S⁴, thereby opening the local circuit and causing the sounder p' to remain inactive.

Having thus described the method of transmitting and receiving the electric currents 125 requisite for simultaneously transmitting two communications in the same direction over a single conductor, it remains to describe the method of applying to the apparatus means for overcoming the detrimental effects due to 130 the difference in the normal potentials of the transmitting terminals, and consequently in

the corresponding earth-connections of the main and artificial conductors in which the receiving-instruments R and R' are included.

With an arrangement of apparatus such as 5 illustrated in Fig. 1, wherein the various batteries or battery-sections at any given station oppose and neutralize each other, I prefer to employ a branch line, l', extending around the series of batteries normally connected with 10 the artificial line, one extremity of the conductor l' being connected with the battery-terminal of the artificial line l, and the other extremity with the earth-terminal 13 at the junction x of the two conductors 11 and 12. 15 The resistance of this circuit l' should be considerably greater than that of the artificial line including the rheostat X. It may in practice be made two or three times as great with advantage, so that in effect it constitutes 20 a shunt or leak around one section or the other of the main battery, according to the position of the key K. It will then become necessary to increase the resistance X until the joint resistance of the lines l and l' is equal 25 to that of the main line L.

It is well known that when an electro-magnet or other like electro-magnetic inductor is placed in a circuit its effect is to oppose the initial flow of the current through its 30 surrounding coil by setting up an opposing electro-motive force, and also to prolong the normal existence of the current, when interrupted, by setting up another electro-motive force, this time in the same direction as the original current. 35 The effect of this action of the inductor I upon the apparatus is as follows: When either or both of the keys K and K' are closed, a positive current is sent to the main line L and a negative current to the artificial line l. The immediate 40 tendency of the current transmitted to the main line is to flow into the line with much greater rapidity at first than after the line has become partially or fully charged. The current transmitted to the artificial line l, however, is opposed in that line by a resistance 45 much greater per unit of length, and the initial flow of the current will be proportionately less through that line. Hence the potentials at the battery terminals of the main and artificial lines differ from each other in proportion to the ratios which the rapidities of the flow of the currents from those points to line bear to each other. The same difference of potential 50 obviously exists at the opposite terminals of the respective batteries or series of batteries, and this difference in potentials tends to result in an uncompensated effect upon the receiving-instruments connected with those poles of the batteries. By properly adjusting the 55 resistance of the branch circuit l' and the retarding effect produced by the inductor I, the escape or flow of the current from the line terminals of each of the batteries or series of batteries may be made practically equal, thereby 60 rendering the potentials at the corresponding terminals of the batteries also equal. The effect

produced upon the receiving-instruments R and R' by each series of batteries will then be entirely neutralized.

When the keys K and K' are operated to 70 reduce or interrupt the flow of current upon the main and artificial lines, the tendency of the artificial line is to discharge instantly, while that of the main line is to discharge more slowly, thereby producing unlike effects 75 upon the receiving-instruments R and R'. This difference in electrical discharge is compensated for and equalized by the comparatively slow discharge on the part of the inductor I in the branch l' of the artificial line l. 80

For the purpose of rendering the retarding effect of the inductor readily adjustable, I construct the same in the manner illustrated in Fig. 2, wherein U represents a supporting-base, upon which are rigidly mounted the coils 85 w of the inductor and a standard, u. Through the centers of the coils w w extend cores i i, which are each constructed of a soft-iron or magnetizable section, i', and a section, i'', of non-magnetic material, such as brass. These 90 two sections are united by a long beveled joint, i'', which construction permits of a careful adjustment of the amount of magnetizable metal included within the coils. The respective extremities of the cores thus formed are secured 95 to two plates, v and v', of non-conducting material, and the entire frame thus formed is movable in the direction of the length of the cores by an adjusting-screw, V, turning in a suitable threaded hole, u', formed in the standard u, the extremity of the screw being attached to the plate v by a swivel-joint, as shown at v'. 100

In the drawings I have shown a modification in the method of carrying out my invention which is especially applicable to systems wherein a locally unopposed battery is normally connected with the main line. Such an arrangement is illustrated in Fig. 3, wherein O' and o' represent two equal sections of a battery having its respective poles connected with the main line L and artificial line l. A conductor, 15, proceeds from a point, y, in the conductor 16, connecting the two sections to the earth at G'. In this conductor is included 110 any suitable form of receiving-instrument, R'. A pole-changing key, K'', similar in construction to the key K, described in connection with Fig. 1, is provided for reversing the connections of the battery-sections O' and o' with 115 reference to the main and artificial lines. A branch conductor, l', extends from a point between the key K'' and the main line L to the point y in the earth-conductor. In this branch conductor is included a condenser, C, having 120 a capacity proportionate to the difference between the electro-static capacities of the main and artificial lines L and l, respectively. The action of this condenser is as follows: When the key K'' is at rest, the positive pole of the 125 battery-section O' is connected with the main line L and its negative pole with the earth 130

through the conductor 15. Consequently the condenser C will receive a certain definite charge, dependent upon the electro-motive force of the battery-section O⁴. The positive 5 and negative poles of the section O⁴ will at the same time be respectively connected with the earth at G' and the artificial line. When the key K³ is depressed, the battery-connections will be reversed with reference to the main 10 and artificial lines, the negative pole of the section O⁴ being now connected with the main line and the positive pole of the section O⁴ with the artificial line. The immediate result of thus reversing the battery-connections will 15 be to produce a greater fall in potential at the terminals of the section connected with the main line than at the terminals of the section connected with the artificial line, in a manner similar to that described with reference to 20 Fig. 1. The necessary result of this difference in potentials would be to establish a current through the conductor 15, connected with the earth, producing a corresponding action of the receiving-instrument included therein. 25 The charge previously stored up in the condenser C, however, enables it to equalize the potentials of the two battery-sections by serving in the capacity of a supplementary battery, it being connected in series with the battery of lower potential—that is to say, the one which for the time being is connected with the main line. Thus its electrically positive and negative plates coincide in direction with the corresponding poles of the battery-section. 30 35 The charge of the condenser will accordingly be added to the current of the battery-section and will act to maintain the requisite degree of potential. The condenser C will, moreover, immediately receive an opposite charge, which 40 in turn will serve to maintain the potential of the opposite battery-section when the key K³ is again reversed.

I claim as my invention—

1. The hereinbefore described method of 45 neutralizing at the transmitting-station the electro-static effects arising from a difference in the respective electrical capacities of the main and artificial lines of a telegraphic system, which consists in modifying the potential 50 of the battery applied to the artificial line comparatively with the changes in the potential of the battery applied to the main line during the transmission of the signal.

2. The combination, substantially as hereinbefore set forth, with the main and artificial 55 lines of a telegraphic system, of a battery and a branch circuit constituting a permanent shunt around a portion of said battery, having an inductive capacity approximately equal to the 60 difference in the inductive capacities of the main and artificial lines.

3. The combination, substantially as hereinbefore set forth, with the artificial line of a duplex or multiple telegraph, of a battery and a 65 branch circuit connected with said artificial

line, constituting a permanent shunt around that portion of said battery which is applied to the artificial line.

4. The combination, substantially as hereinbefore set forth, with the artificial line of a duplex or multiple telegraph, of a main battery, a branch circuit connected with said artificial line and constituting a permanent shunt around the portion of said battery which is applied to the artificial line, and an electro-magnetic inductor included in the said branch circuit. 75

5. The combination, substantially as hereinbefore set forth, with the artificial line of a duplex or multiple telegraph, of a battery, a branch circuit connected with said artificial line and constituting a permanent shunt around a portion of said battery, an electro-magnetic inductor included in said branch circuit, and means for adjusting the energy and duration 80 of the electric discharge from said inductor. 85

6. The combination, substantially as hereinbefore set forth, with the main and artificial lines of a duplex or multiple telegraph, of two electrically equal and similar series of batteries or battery-sections, means, substantially 90 such as described, for transmitting from said batteries through said main line currents of three different strengths and given polarity, and simultaneously transmitting upon the artificial line currents of equivalent strengths 95 but opposite polarity, and a branch line constituting a shunt around the portion of said battery-sections connected with said artificial line.

7. The combination, substantially as hereinbefore set forth, with the main and artificial lines of a duplex or multiple telegraph, of two series of battery-sections, the opposite poles of which are respectively connected with said main and artificial lines, each series comprising 105 three sections, the sum of the electro-motive forces of two of said sections being equal and normally opposite to that of the remaining section, and means, substantially such as described, for simultaneously interchanging 110 the circuit-connections with reference to the main line of one or both the corresponding lesser battery-sections in each series.

8. The combination, substantially as hereinbefore set forth, with the main and artificial 115 lines of a duplex or multiple telegraph, of two or more batteries or battery-sections having their opposite poles respectively connected with said main and artificial lines and their remaining poles with the earth, and a receiving-instrument having one of its two coils included in said main and the other in said artificial line. 120

In testimony whereof I have hereunto subscribed my name this 16th day of November, 125 A. D. 1882.

ALEXANDER MUIRHEAD.
